UNITED STATES PATENT OFFICE

JAMES L. BREESE, JR., OF CHICAGO, ILLINOIS, ASSIGNOR TO OIL DEVICES CORPORATION,
OF CHICAGO, ILLINOIS, A CORPORATION OF ILLINOIS

HYDROCARBON BURNER

Application filed November 17, 1927. Serial No. 233,787.

My invention relates to a device for burning hydrocarbons, which is particularly adapted for the burning, in heating plants, of a liquid hydrocarbon. One object of my invention is to provide a simple and easily manufactured complete fuel supply and heating unit adapted for installation in any suitable heater. Another object is the provision of clamping means for sealing off the air in the ash pit door. Other objects will appear from time to time in the course of the specification and claims.

I illustrate my invention more or less diagrammatically in the accompanying drawings, wherein—

Figure 1 is a perspective view of my device, showing the heating unit withdrawn from the heater or stove;

Figure 2 is a vertical section of the heating unit positioned within the heater;

Figure 3 is a section along the line 3—3 of Figure 2;

Figure 4 is an enlarged top plan view of the combination oil and gas inlet;

Figure 5 is a section along the line 5—5 of Figure 4; and

Figure 6 is a vertical section along the line 6—6 of Figure 5.

Like parts are indicated by like symbols throughout the specification and drawings.

It will be realized that I describe and illustrate a complete fuel supply and burner unit which is adapted to be used with any suitable heater, the combustion member of the burner being for example placed within the ash pit of a coal burning heater.

A generally indicates a heater of a well known type having the usual supporting legs A¹, a flue escape pipe A² and a fire door A³.

B indicates a fuel supply and heater unit having a combustion member B¹. The latter includes a bottom portion B² resting upon the bottom of the ash pit A⁴ of the heater A, and provided with the upwardly projecting generally cylindrical wall B³ in communication with which is the longitudinal air inlet passage B⁴, which is braced by the member B⁵ to the wall B³. Said wall may be provided with indentations B⁶ for clearing

the lugs A⁵ or other projections inside the ash pit opening.

Seated upon the upper edge of said wall is a mixing chamber having the bottom portion C which may be concave as shown and the upwardly projecting cylindrical side wall C¹, which may be made of two parts C² C³ secured together by the crimp C⁴. C⁵ are a plurality of large and small apertures penetrating the upper part C³ of the wall, permitting air to enter the mixing chamber. Externally projecting from the wall C¹ is a circular flange C⁶ with a downwardly projecting ring C⁷ adapted to be seated upon the upper edge of the drum B³. C⁸ is a conic shaped split ring positioned in the circular depression or groove C⁹ in the wall C¹.

D generally indicates a gas and fuel inlet having a top portion D¹ which may be hexagonal in shape, and has an annular channel D² in its lower side. Projecting downwardly from the portion D¹ and centrally located within said channel D² is the conical portion D³ associated with a downwardly extending stem D⁴ having an outwardly projecting flange D⁵ with a conical-shaped end portion D⁶. As best illustrated in Figures 5 and 6 the flange D⁵ and conical end portion D⁶ seat in a correspondingly shaped depressed portion C¹⁰ centrally located and integral with the concave bottom C of the mixing chamber. D⁷ are a plurality of passages in the stem D⁴, extending from the fuel passage D⁸. D⁹ are a plurality of downwardly inclined gas outlet passages extending from the chamber D¹⁰ above the tube or pipe D¹¹ screwthreaded into the member D as at D¹². The other end of said stub pipe is threaded into the member E as at E¹. The member E is an elbow with a side outlet. It is provided with a seat E² adapted to receive the correspondingly shaped depressed portion C¹⁰. The member E and member D are secured to the bottom C of the mixing chamber and held in place by means of the tube D¹¹, to which they are screw-threaded.

E³ is a liquid fuel pipe screwthreaded into the member E, communicating with the fuel passage E⁴. In line with the lower open end of the tube D¹¹ is a gas passage E⁵ separated 100

from the fuel passage E⁴ by means of a wall E⁶. E⁷ is a gas supply line communicating with the passage E⁵. As best shown in Figures 4, 5 and 6, gas for the necessary pilot lights for igniting of the liquid hydrocarbon fuel has free access to the mixing chamber by means of the passage E⁶, tube D¹¹ and passage D¹⁰ communicating with the gas outlets D⁹. The downwardly inclined flames of the pilot lights will be in the direct path of the liquid fuel flowing through the apertures D⁷. Integral with the member E is a boss E¹⁰ downwardly projecting through the hole B⁷ located in the upwardly depressed portion B⁸ of the bottom B². E¹² is an aperture in the boss E¹⁰ adapted to receive the locking pin E¹³, thus securing the mixing chamber to the air drum B³.

F indicates a fuel tank having a conical bottom plate F¹. F² is a fuel control valve responding to the action of the float F³ in the float chamber F⁴. Upwardly extending above the upper edge of the fuel tank F is the rotary stem F⁵ for controlling the flow of liquid fuel through the valve F². F⁶ is a cover. The float chamber F⁴ is provided with an outwardly projecting circular flange F⁷ upon which is seated the fuel tank F, centered by means of the upwardly extending flange F⁸ and held in place by the split locking band F⁹. Mounted in the flange F⁷ at either side of the float chamber are the supporting rods F¹⁰ F¹¹, having the adjustable base members F¹² with locking screws F¹³.

35 Communicating with the float chamber F⁴ is the upwardly extending pipe G associated with the fuel line E³. As illustrated in Figures 2 and 3, the fuel line E³ and gas supply pipe E⁷ are positioned within the air inlet passage B⁴ which may be supported by braces B¹⁰ or other suitable means. The fuel line E³ is provided with a control valve G¹ having the upwardly protruding handle G².

Figures 2 and 3 illustrate the heating unit 45 with the combustion member positioned within the ash pit A⁴. The usual ash pit door of the heater A has been removed and been replaced by the closure plate H cut away as at H¹ to conform to the shape of the laterally projecting air passage B⁴. H² is a locking member, hinged as at H³ to the usual pin H⁴ provided for the ash pit door. H⁵ H⁶ are spring members mounted on the member H² adapted for frictional engagement with 55 the plate H, pressure being applied by means of the screwthreaded stud H⁶ mounted in the heater A and penetrating the locking member H² and the wing nut H⁷.

It is understood that the usual grating associated with the heater A may preferably be removed as shown, leaving free access to the combustion chamber A⁷.

It will be realized that whereas I have shown a practical and operative device, nevertheless many changes might be made in

size, shape, number and distribution of parts without departing from the spirit of my invention. I therefore wish my drawings and description to be taken as in a broad sense illustrative or diagrammatic, rather than as limiting me to my specific description and showing.

The use and operation of my invention are as follows:

The heater unit herein shown may be applied to any heater, for example a coal burning heater, by merely lifting off the ash pit door and removing the grates and inserting the mixing chamber. This ready conversion of a coal burning plant to an oil burning plant is of great importance.

Referring to the unit itself oil flows from the float chamber F⁴ along the line E³ to the elbow member shown in detail in Figures 4, 5 and 6. The elbow member also receives gas through the line E⁷. It will be noted that the gas and oil flow upwardly through the same member, although being supplied of course through different ducts to the bottom of the mixing chamber. The gas jets which pass through apertures D⁹ incline downwardly into the path of delivery of the oil through the passages D⁷, the gas jets being vertically aligned with the oil ducts.

In order to prevent the inflow of air through the grate door, the grate door being removed, I provide the structure shown in detail in Figures 2 and 3 which includes the plate H, cut away as at H¹ to conform to the air passage E⁴, upon which it may rest. In order to hold it against the edges of the grate door I provide vertical spring arms H⁵ which are secured to the transverse strip H², one end of which is hinged to the normal pivot pin H⁴ of the ash pit door, whereas the other is secured at the opposite side of the door, for example by the screwthreaded stud H⁶ and the ring nut H⁷. The result is a constant yielding pressure against the closure member H, which keeps it tightly sealed in place the pressure being applied particularly to the four corners of the plate.

I claim:

1. As a new article of manufacture, a self-contained hydrocarbon burner and fuel storage unit adapted to be applied to a furnace, such unit including a mixing chamber and an air chamber thereabout and an air passage extending outwardly from said air chamber, the mixing and air chamber being adapted to be positioned within the furnace during normal use of the device, the air passage extending exteriorly from said furnace, a fuel line inwardly extending through said air passage and in communication with the mixing chamber, and a fuel tank in communication with the opposite end of said fuel line, and supporting means for said tank, the various parts of the unit so formed being permanently positioned in relation to each other,

- the unit as a whole being freely removable from the furnace.
2. As a new article of manufacture, a self-contained hydrocarbon burner and fuel storage unit adapted to be applied to a furnace, such unit including a mixing chamber and an air chamber thereabout and an air passage extending outwardly from said air chamber, the mixing and air chamber being adapted to be positioned within the furnace during normal use of the device, the air passage extending exteriorly from said furnace, a fuel line inwardly extending through said air passage and in communication with the mixing chamber, and a fuel tank in communication with the opposite end of said fuel line, and supporting means for said tank, the various parts of the unit so formed being permanently positioned in relation to each other, said fuel line being adapted to serve as the spacing and connecting means for said mixing chamber and fuel tank, the unit as a whole being freely removable from the furnace.
3. As a new article of manufacture, a self-contained hydrocarbon burner and fuel storage unit adapted to be applied to a furnace, such unit including a mixing chamber and an air chamber thereabout and an air passage extending outwardly from said air chamber, the mixing and air chambers being adapted to be positioned within the furnace during normal use of the device, the air passage extending exteriorly from said furnace, a fuel line inwardly extending through said air passage and in communication with the mixing chamber, a float chamber to which the outer end of the fuel line is secured and a fuel tank positioned upon said float chamber and supporting means for said float chamber and fuel tank, the various parts of the units so formed being permanently positioned in relation to each other, the unit as a whole being freely removable from the furnace.
4. As a new article of manufacture, a self-contained hydrocarbon burner and fuel storage unit adapted to be applied to a furnace, such unit including a mixing chamber and an air chamber thereabout and an air passage extending outwardly from said air chamber, the mixing and air chambers being adapted to be positioned within the furnace during normal use of the device, the air passage extending exteriorly from said furnace, a fuel line inwardly extending through said air passage and in communication with the mixing chamber, a float chamber to which the outer end of the fuel line is secured and a fuel tank positioned upon said float chamber and supporting means for said float chamber and fuel tank, the various parts of the units so formed being permanently positioned in relation to each other, the unit as a whole being freely removable from the furnace, the above mentioned supporting means for the tank be-
- ing adjustable to adjust the height of said float chamber and tank.
5. As a new article of manufacture, a self-contained hydrocarbon burner and fuel storage unit adapted to be applied to a furnace, such unit including a mixing chamber and an air chamber thereabout and an air passage extending outwardly from said air chamber, the mixing and air chambers being adapted to be positioned within the furnace during normal use of the device, the air passage extending exteriorly from said furnace, a fuel line inwardly extending through said air passage and in communication with the mixing chamber, a float chamber to which the outer end of the fuel line is secured and a fuel tank positioned upon said float chamber and supporting means for said float chamber and fuel tank, the various parts of the units so formed being permanently positioned in relation to each other, the unit as a whole being freely removable from the furnace, the above mentioned supporting means for the tank being adjustable to adjust the height of said float chamber and tank, said mixing and air chambers being formed to be positioned upon the bottom of the furnace with which the unit is used.
- Signed at Chicago, county of Cook, and State of Illinois, this 14th day of November, 1927.
